UNITED STATES PATENT OFFICE

WILLIAM L. VALIQUETTE, OF DAYTON, OHIO, ASSIGNOR TO THE HARRIS-SEYBOLD-POTTER COMPANY, OF DAYTON, OHIO, A CORPORATION OF DELAWARE

GAUGE FOR PAPER-CUTTING MACHINES

Application filed February 3, 1927. Serial No. 165,734.

My invention relates to means for gauging the successive cuts in paper cutting machines, whereby a quick and accurate adjustment of the paper pile may be made in order that successive cuts may be at accurate right angles to each other.

It has been customary in the past to provide a movable and accurately adjustable back gauge for the paper pile, and in connection therewith, to provide a fixed side gauge against which the paper pile is to be adjusted for the next successive cut. While the back gauge and fixed side gauge have been disposed at accurate right angles to each other, when the front cut has been made and the paper pile is given a quarter turn for the second, if it so happens that the rear uncut edge of the pile thus turned is not at right angles to the first cut, it is necessary to jog the pile accurately against the side gauge. To accomplish this takes considerable time and trouble where the side gauge is fixed, and in addition the adjustment may not be accurate.

It is to remedy this difficulty that my invention is directed, and it consists of that certain novel construction and arrangement of parts whereby the side gauge may be movable and readily and easily adjusted against the paper pile to obtain the desired accurate right angle cut for the successive operations on the paper.

I have illustrated only so much of the paper cutting machine as may be necessary to explain the construction and operation of the side gauge.

In the drawings:—

Figure 1 is a plan of one corner of the cutting table showing the position of the gauges.

Figure 2 is a side elevation of same.

Figure 3 is a cross section on the line 3, 3, of Fig. 2.

The cutting table is indicated at 1 supported on the usual side standards 2 which carry and support the clamp and cutting knife and the operating mechanism for the same. The usual back gauge is indicated at 3, the front edge of which is set accurately parallel to the cutting knife indicated at 4. This back gauge slides in the usual grooves in the table

top, and is adjustable in the usual way by the indexed band wheel indicated at 5.

The side gauge is set at accurate right angles to the knife and comprises a bar 6 which is mounted near either end on studs 7, 8, 9 and 10. These studs slide in a plate 20, and the studs for each pair are threaded right and left and carry gears similarly threaded. The gears 15, 15 and 16, 16 are held from longitudinal movement on the screw threaded studs by bearing plates 11, 12 which are secured by bolts 13 to the plate 20. The gears are engaged by a rack bar 17 which extends between each pair, the rack bar being provided with a handle 18 extending out in front in convenient reach of the operator. It will be obvious from this construction that the rotation of the gears under the action of the rack bar will drive the studs to slide in the plate 20 and adjust the side gauge out and in while maintaining its right angled relation to the knife cut.

With this construction, all the operator has to do when he turns the paper pile for the second cut is to operate the rack bar and bring the side gauge up to the cut edge of the pile and the second cut will be at accurate right angles to the previous cut.

While I have shown one construction for adjusting the side gauge, which I prefer, I do not wish to be limited in the claims that follow to the particular construction shown, as other mechanism for adjusting the side gauge without changing its right angled relation to the travel of the cutting knife, will fall within the spirit of my invention.

Having thus described my invention what I claim as new and desire to secure by Letters Patent is:—

1. In a paper cutting machine, the combination with a cutting table, cutting knife and an adjustable back gauge for the paper pile, of a side gauge with means for reciprocating same in a plane at right angles to the plane of the cutting knife with a jogging motion, for the purpose described.

2. In a paper cutting machine, the combination with a cutting table, cutting knife and an adjustable back gauge for the paper pile, of a side gauge set at right angles to the cut-

ting knife, and means for reciprocating said side gauge in parallel lines with a jogging motion.

3. In a paper cutting machine, the combination with a cutting table, cutting knife and an adjustable back gauge for the paper pile, of a side gauge set at right angles to the cutting knife, studs for holding the side gauge in its set position, and means for driving said studs to reciprocate said side gauge in parallel lines.

4. In a paper cutting machine, the combination with a cutting table, cutting knife and an adjustable back gauge for the paper pile, of a side gauge set at right angles to the cutting knife, studs for holding the side gauge in its set position, gears threaded on said studs, and means for rotating said gears to reciprocate the side gauge in parallel lines.

5. In a paper cutting machine, the combination with a cutting table, cutting knife and an adjustable back gauge for the paper pile, of a side gauge set at right angles to the cutting knife, studs for holding the side gauge in its set position, a plate to guide the studs with gears threaded on the studs, and means for rotating the gears to reciprocate the side gauge in parallel lines.

6. In a paper cutting machine, the combination with a cutting table, cutting knife and an adjustable back gauge for the paper pile, of a side gauge set at right angles to the cutting knife, studs for holding the side gauge in its set position arranged in pairs, a plate to guide the studs with gears threaded oppositely on said studs, and a rack bar simultaneously engaging said pairs of gears to drive said studs and to reciprocate the side gauge in parallel lines.

7. In a structure of the class described, the combination of a table, a gauge support mounted at the side of the table, a gauge bar, pairs of oppositely threaded adjusting screws slidable in said support and connected to said gauge bar, pairs of adjusting pinions having threaded engagement with said screws, and a rack bar arranged between said pairs of pinions whereby they are simultaneously rotated as the rack bar is reciprocated.

8. In a structure of the class described, the combination of a table, a gauge support mounted at the side of the table, a gauge bar slidably mounted on said support, adjusting screws for said gauge bar, adjusting members having threaded engagement with said adjusting screws, means for simultaneously actuating said adjusting members, and a second gauge member adjustably mounted on said table at right angles to said gauge bar.

9. In a structure of the class described, the combination of a table, a gauge bar, adjusting screws at each end of said gauge bar, disposed transversely thereto, means for simul-

taneously adjusting said screws whereby the bar is uniformly adjusted, and a second gauge disposed at right angles to said gauge bar.
